UNITED STATES PATENT OFFICE.

JOHN F. CAVANAGH, OF MERIDEN, CONNECTICUT, ASSIGNOR TO THE CONNECTICUT TELEPHONE & ELECTRIC COMPANY, OF MERIDEN, CONNECTICUT, A CORPORATION OF CONNECTICUT.

DISTRIBUTER-ARM.

1,248,612.

Specification of Letters Patent.

Patented Dec. 4, 1917.

Application filed June 11, 1917. Serial No. 174,114.

To all whom it may concern:

Be it known that I, JOHN F. CAVANAGH, a citizen of the United States of America, residing at Meriden, Conn., have invented a new and useful Distributer-Arm, of which the following is a specification.

This invention relates to ignition apparatus and the general objects of the invention are to provide an accurate and at the same time simple and practical connection between the distributer arm and the distributer shaft.

Accordingly, my invention consists in part, in constructing the distributer arm, which is usually molded in suitable insulating material, with a bore to fit over the distributer shaft, said bore having radial projections at separated points therein to engage the shaft and portions between said bearing projections recessed away from the shaft. A further feature is the provision of oppositely disposed drive shoulders within the bore separated from each other and disposed to engage a driving tang on the end of the distributer shaft.

Other features and details of construction will become apparent as the specification proceeds.

In the accompanying drawing I have illustrated my invention as embodied in practical and at present preferred forms, but I would have it understood that changes and modifications may be made without departing from the true spirit and scope of the invention.

In this drawing:—

Figure 1 is a broken sectional view of an ignition distributer having my invention incorporated therein.

Fig. 2 is a bottom plan view of the distributer arm as detached from the upper end of the distributer shaft, shown also in top plane in this view, illustrating in dotted lines the position of the distributer shaft within the bore of the arm.

Fig. 3 is a bottom plan view of the arm in a slightly modified form.

Referring particularly to Fig. 1, 5 designates the distributer shaft driven from the engine by suitable gearing and constructed in the illustration, as customary, with one side of the upper end portion thereof cut away to provide a driving tang 6. This upper end portion of the shaft is usually

substantially cylindrical as illustrated to receive the hub of the distributer arm.

The distributer arm 7, is usually molded to shape in suitable insulating material and in general is formed with a hub portion 8, fitting over the shaft and an outstanding arm 9, carrying a distributer contact 10, the end of this contact in the rotary movement of the arm coming into operative relation with suitable relatively stationary contacts 11, and current being supplied to the rotary contact by a spring brush 12, which bears against a current conducting point 13.

The details of the connection between the shaft and distributer arm will perhaps be best understood by reference to Fig. 2, where-in it will be seen that the hub portion of the arm is formed with a generally cylindrical bore 14 to receive the end of the shaft and inwardly projecting radial extensions 15 at different sides of said bore for engagement with the walls of the shaft. In practice, the bore is made slightly larger than the diameter of the shaft and the bearing projections 15 project radially inward just far enough to engage with and center the arm upon the shaft. This condition is illustrated by the dotted lines in Fig. 2, which show how the radial projections bear upon the shaft and the portions between said bearing projections are recessed away from the shaft. The result of this construction is that the distributer arm is accurately centered upon the shaft, irrespective of slight irregularities in the molding operations and in spite of certain shrinkages which are likely to occur in molded articles of this character.

The arm is keyed upon the shaft and caused to rotate therewith by providing it, in this invention, with drive shoulders 16, projecting inwardly into the bore at opposite sides thereof and terminating in abrupt shoulders 17 to engage the driving face of the tang 6, these drive shoulders being disconnected from each other as shown in Fig. 2, so as to engage the tang at separated points. By means of this construction, the bore is substantially symmetrical, so that any shrinkage which may occur will be more or less regular and will not distort the shape of the bore. This construction furthermore provides a firm driving engagement at two relatively widely separated points between

the driving tang and the arm, causing the arm to move positively therewith.

In the form shown in these first two figures, the distributor arm contacts with the shaft in but four places. Friction is therefore reduced to a minimum, enabling the arm being readily placed upon and removed from the shaft. Also, it will be seen that if the stock should shrink to a point which would be prohibitive in the old style arm, which is made to contact with the shaft at all points circumferentially, a slight effort merely is required to slip the distributor arm over the end of the shaft, the shaft in some cases having a broaching effect on the projections of the bore as the arm is forced in place thereover. With my new construction furthermore, any slight distortion from the circular has no ill effect upon the mounting of the arm on the distributor shaft.

The number and shape of the bearing projections may be varied. For instance, as shown in Fig. 3 there may be only three bearing projections disposed equidistantly about the bore, this providing the three-point support, desirable in mechanisms. The projections in this case also are shown more in the nature of ribs, as distinguished from the rather flat style of projections shown in the first form.

Another feature of my invention which is of considerable practical importance from a manufacturing standpoint is that the core or pin which is used to mold the bore in the distributor arm may be made as a solid pin, except for the slight depressions in the sides thereof, necessary to form the ribs or bearing projections and the relatively small pockets in the end thereof necessary to form the two separated drive shoulders. This practically solid construction of the pin allows for the pin being hardened as much as necessary for practical molding purposes without the danger of breaking the pin, due to fragility of any of its parts. This feature will be fully appreciated when it is realized that this pin or core used in forming the bore should be made quite hard to resist the abrasive action of the molding material and when it is understood further that it has been impractical heretofore to make the pin as hard as desirable because when so made, the projection or tang on the end of the pin had a tendency to break off in the mold.

The advantages of the invention will be more fully appreciated when it is realized

that heretofore there has always been considerable waste in molding articles of this character, because of the fact that the concentric or circular seat in the distributor arm had to be molded very close to size so as to accurately fit the distributor shaft, and that even a relatively slight shrinkage or distortion would make these close fitting members unfit for use. As there is practically always some shrinkage in these articles, it can be understood that the percentage of unusable products was relatively high. The present invention makes it possible to mold the ribbed portions of the bore in the distributor arm accurately to size and then, even though some shrinkage does take place, said distributor arms may still be used by simply forcing the arm over the end of the distributor shaft, the shaft acting in such cases, as above indicated, in a broaching capacity to mill off the high points on the ribs, producing an accurate and close fitting engagement between the shaft and distributor arm.

What I claim is:—

1. In combination with a distributor shaft having the end portion cut away at one side thereof to provide a driving tang and a distributor arm of insulating material having a shaft-receiving bore to fit the end portion of the shaft, and separated drive shoulders projecting into opposite side portions of said bore to engage the driving tang at 90 separated points thereon.

2. As an article of manufacture, a distributor arm of insulating material arranged to be mounted on a shaft of an igniter mechanism, said arm having a bore approximately fitting the end of said shaft, inward projections on the walls of said bore arranged to be partially cut-away by the shaft upon the application of said arm thereto whereby a snug fit may be obtained between 100 said parts.

3. As an article of manufacture, a distributor arm of insulating material arranged to be mounted on a shaft of an igniter mechanism, said arm having a bore approximately fitting the end of said shaft, inward projections on the walls of said bore arranged to be partially cut-away by the shaft upon the application of said arm thereto whereby a snug fit may be obtained between 105 said parts, said inward projections being in the form of longitudinally arranged spaced ribs.

JOHN F. CAVANAGH.
